(57) **CLAIM**

We claim the ornamental design for a harness, as shown and described.

DESCRIPTION

FIG. 1 is a perspective view of a harness showing our new design;

FIG. 2 is another perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines illustrate features of the harness that form no part of the claimed design.
